United States Patent Office

Des. 227,994
Patented July 31, 1973

227,994

INPUT TERMINAL

John Keenan, Northport, N.Y., assignor to Effkay
Development Corporation, Huntington, N.Y.

Filed Dec. 29, 1971, Ser. No. 214,537

Term of patent 14 years

Int. Cl. D14—02

U.S. Cl. D26—5 C

FIG. 1

FIG. 2

FIG. 3

FIG. 4

FIG. 5

FIG. 1 is a top plan view of the input terminal, embodying my new design;

FIG. 2 is a front elevational view of the device of FIG. 1;

FIG. 3 is a right side elevational view thereof;

FIG. 4 is a left side elevational view of the device of FIG. 1; and

FIG. 5 is a rear elevational view of the device of FIG. 1.

I claim:

The ornamental design for an input terminal, as shown.
